CLAIM

The ornamental design for the pocket, as shown and described.

DESCRIPTION

FIG. 1 is a front view of a pocket in a closed orientation; FIG. 2 is a front view of the pocket in a partially open orientation; and,

FIG. 3 is a front view of the pocket in a fully open orientation.

The dash-dash-dash-dash type broken lines shown in the drawings are included for the purpose of illustrating environmental structure and form no part of the claimed design. The dot-dash-dot-dash type broken lines shown in the drawings define the boundaries of the claimed design.

1 Claim, 3 Drawing Sheets(56)
